DRIER AND METHOD OF DRYING

Emil Ericksson, Chicago, Ill., assignor to Standard Process Corporation, Chicago, Ill., a corporation of Delaware

Original application September 22, 1932, Serial No. 634,406. Divided and this application September 5, 1936, Serial No. 99,671

20 Claims. (Cl. 101—416)

The present invention relates to novel drying and treating apparatus and methods of drying and treating, and more particularly to novel drying methods and means for use in combination with a multiple impression printing press and the web printed thereby, this application being a division of my application Serial No. 634,406, filed September 22, 1932.

While the present invention is capable of use in any instance where a coated or printed strip or the like is used, the present invention will be described in connection with a preferred embodiment designed for use with a multiple impression printing press.

One of the most serious problems encountered in the use of multiple printing presses in the past has been the inability to properly dry the printed surfaces of the strips or webs between successive impressions of the press. This inability to properly dry the successive impressions has materially reduced the field of use for presses of this character since it has been impossible heretofore, to operate such presses at the desired high speeds and at the same time produce clear cut impressions on the travelling web.

It is therefore a primary object of the present invention to provide novel drying apparatus capable of drying coated surfaces between relatively rapid and successive applications of coating material in order that the rate of production of coated material may be increased over that heretofore possible.

A further object of the present invention resides in the provision of novel drying means and methods for use in combination with a multiple impression printing press whereby the strip or web is rapidly dried between successive printing impressions and the printing or coating can be done at a relatively high rate of speed.

Another object of the present invention is the provision of novel drying means and methods for use in combination with a multiple impression printing press wherein the successive impressions are dried at a rate sufficient to permit successive superimposed impressions on the same portion of the web surface with the press operating at relatively high speed.

A still further object of my invention lies in the provision of a novel method of drying successive applications of ink or coating material by projecting a drying fluid onto the material to be dried and immediately withdrawing the drying fluid to maintain a sufficiently high rate of circulation to permit of successive application

of ink or coating material at a relatively high rate.

A further object of my invention lies in the provision of a novel method of drying ink on a printed surface quickly and effectively by heating the inked surface and cooling it to crystallize the ink at a rate to permit of rapid and successive applications of ink to the surface.

A still further object of my invention lies in the provision of a novel method of drying ink on a printed surface by the continuous projection of both heated and cooled fluid onto the surface and immediate and continuous withdrawal of the heated and cooled fluid and resultant fumes from the surface.

Another object of the present invention resides in providing a novel treater or dryer comprising alternately arranged blower and suction nozzles disposed in relatively close relation to each other to permit of rapid treatment.

A further object of the present invention resides in the provision of a drier having heating, cooling and exhausting chambers provided with independent nozzles so arranged that each heating or cooling nozzle has an exhaust nozzle cooperating therewith.

Another object of the present invention resides in the provision of a novel nozzle and chamber construction for a high speed printing press drier comprising alternate blower and suction nozzles.

A still further object of the present invention resides in the provision of a novel nozzle structure for use on a drier wherein currents of drying fluid are directed against the surface to be dried in a substantially tangential direction.

The foregoing and other objects of the invention will appear in the following description of the preferred embodiments and preferred methods taken in conjunction with the attached drawings, wherein:

Figure 1 is a side-elevational view of a preferred embodiment of my invention illustrating the relative positions of the driers and impression cylinders of the present invention, the printing press, the web roll and final drying stand being shown in section.

Figures 2 and 3 are rear and side-elevational views of a preferred embodiment of the novel drying means interposed between the impression cylinders of the press.

Figure 4 is a fragmentary section of the drier of Figures 2 and 3 to show the manner in which the partitioning members of the drier of Figure 3 are secured at the center of the drier.

Figure 5 is a fragmentary elevation showing how the drier of the present invention may be supported on the frame members of the printing press.

Figure 6 is a top plan view of a preferred embodiment of the novel drying means provided on the final drying stand of Figure 1 with the cover thereof removed.

Figure 7 is an enlarged longitudinal cross-sectional view of the drier of Figure 6; and,

Figure 8 is a fragmentary section showing the manner in which the heater supports are fastened to the housing in the form of drier shown in Figures 6 and 7.

Referring to the drawings wherein like reference numerals are used to indicate like parts in the several figures, a printing press, indicated generally by reference character 11, and a web reel stand or paper holder 12, described more fully in my copending application Serial Number 634,406, filed September 22, 1932, having a preferred combination of the novel drier of the present invention incorporated therewith, are shown by way of example.

Press 11 is provided with a normally idling impression cylinder 13 having a suitable impression surface 14, preferably of a yielding substance such as rubber or the like. Spaced about the periphery of impression cylinder 13 are mandrels or printing cylinder holders 16, 18, 19 and 21 which receive readily removable, thin printing cylinders or shells 22, held firmly thereon. Shells 22, and the methods of forming and utilizing them, are fully disclosed and claimed in my copending applications Serial Numbers 418,916 and 525,267. Different colors or the same color may be printed by each of cylinders 16, 18, 19 and 21 if desired.

Web 23, which may be of any substance such as paper, textile material, regenerated cellulose or the like, upon the surface of which it is desired to print, is passed from material rolls 24 or 26 through guide rolls 27-27 and over roller 28 under proper tension, regulated by tensioning means 29, of any suitable construction.

Web 23 prior to its entry between the printing couples formed by impression surface 14 and printing cylinders is guided over guide rolls 32, 33 and 34. Web 23, after passing between the final printing couple comprising cylinder 21 and impression surface 14, is guided over roll 35 after which it may pass to web roll stand 12 if desired for final treatment by the web drying and treating means thereon and wound or otherwise conveniently taken care of by any desired means not shown which draws it under desired tension from press 11 through the final treating means. Guide rollers 32, 33 and 35 are supported for adjustment from any suitable adjustable support 36 as fully described in the application of which this is a division.

A preferred embodiment of my drying and treating apparatus 37 is supported on a pair of spaced main frame members 38 and 39 at the position shown in the illustrated embodiment of the press such that as web 23 progresses beneath a printing cylinder and receives a printed impression therefrom, it passes the treating apparatus 37 prior to its passage between the next printing couple. Driers 37, following this plan of disposition, are located after each of printing cylinders 16, 18 and 19.

It is obvious that if desired a drier 37 could be mounted on frame members 38 and 39 to dry the ink on web 23 after its passage under

printing cylinder 21. However, I prefer to pass web 23 through a modified form of drying and treating apparatus indicated by reference character 40 and mounted on top of paper roll stand 12 through which web 23 passes from guide roll 35. It is to be understood that driers 37 and 40 may be used interchangeably if desired, and that while these embodiments thereof are illustrated in connection with the press illustrated in the drawings, the novel drying methods and apparatus about to be described may be used for drying any coated surface or any material from which moisture or a volatile is to be removed.

I will now describe in detail one of the driers 37 and by way of example will select that one of the driers lying between printing cylinders 19 and 21 which is illustrated in detail on Figures 2 and 3 of the drawings.

Referring to these figures, drier 37 comprises an outer casing member 41 formed preferably from sheet metal. Sheet metal partitions 42 and 43 within casing member 41 provide three chambers 44, 45 and 46, respectively. Chambers 45 and 46 are closed at their sides by walls 47 and 48 spaced inwardly from side walls 49 and 52 of outer casing member 41. Chamber 44 includes end compartments 53 and 54. A plurality of nozzle members 55, carried by and suitably secured to bars 56, extend across the bottom of chambers 45 and 46 substantially the full width thereof. An external opening 57 is provided in each nozzle member between the inturned edges 58 for a purpose to be described.

Nozzle members 55 are spaced from each other longitudinally of casing member 41 to provide ducts 59, preferably inclined as shown, extending substantially the entire width of chambers 45 and 46 and in direct communication therewith. Similar ducts 61, preferably inclined as shown, are in direct communication with chamber 46. Nozzles 55 are in communication with spaces 53 and 54 of chamber 44.

Elongated strips of sheet material 62 having an inturned flange 63 in contact with the end wall of casing member 41 and an inclined lip 64 formed by the inturned edge of casing 41 provides an end nozzle 65. Nozzle 65 is in direct communication through apertures 66 with chamber 44 through passage 67 defined by casing member 41 and partition 42.

A similar strip 68 at the opposite end of casing member 41 provides an end nozzle 69 in direct communication through apertures 71 with chamber 44 through a like passage 67.

Plate 72, curved between its ends, has flat portions 73 and 74 lying loosely in contact with walls 75 and 76 of partitions 42 and 43, respectively, walls 75 and 76 being suitably bent as at 77 to permit them to extend inwardly between strips 56. The ends of flat portion 78 of plate 72 overlie strips 56 and portion 78 is provided with an elongated slot or aperture 79. An elongated slot 81 is provided in central nozzle 82 with its center substantially in alignment with the center of slot 79.

A stiffening member 83, slotted to conform with slot 81, is soldered or otherwise secured to the inside wall of nozzle 82. The parts described are adjustably connected together by suitable means illustrated as bolt 84 in slots 79 and 81. Wing nut 85 engages flat portion 78 of plate 72 to clamp strip 56 between nozzle 82 and plate 72, at the same time bringing plate 72 in contact with walls 75 and 76 of partitions 42 and 43 to retain them in position. Angles 77 permit walls

78 and 79 to overlie nozzle 82. Conduit connection 88 extends within casing member 41 and communicates with chamber 45. A suitable fitting 87 is provided on conduit connection 88 for connection to conduit 89 (Figure 1) connected to a suitable source of cool air.

Conduit connection 89 extends within the casing member 41 and communicates with chamber 48. A suitable fitting 81 is provided for connection with conduit 92 (Figure 1) which is connected with a source of heated air. Conduit connection 93 opens directly into space 67 of chamber 44. A suitable coupling member 94 is provided for connection with conduit 95 (Figure 1) which is connected to a suitable exhausting apparatus such as a suction fan. Each of the driers 37 is provided with conduit connections just described for connection with conduits which are or may be connected to common sources of cool air, heated air, and a common exhausting apparatus, if so desired. The conduit connections to driers 37 lying between printing cylinders 18 and 19 may be connected as illustrated through the wall of casing member 41 opposite nozzles 55. Drier 37, lying between printing cylinders 16 and 18, is supported from frame members 38 and 39 by brackets 96 (Figure 1). Brackets 96 are secured to main frame members 38 and 39 by suitable means, as bolts 97. Inwardly extending arms 98 of brackets 96 carry vertically disposed cross-members 99. Cross-members 99 are provided at their ends with upper and lower threaded apertures 100.

Supporting bars 101 and 102 are suitably secured to casing member 41 of drier 37, as for example by a plurality of short bolts 103 secured in brackets 104 which are soldered or otherwise suitably connected to casing member 41. Supporting bar 101 is provided with notches 105 at its end, which notches enable bar 101 to be hung over thumb screws 106 which are threaded into the above mentioned upper apertures 100 in cross-members 99. Similar notches 105 are provided in the ends of bar 102 to cooperate with thumb screws 106 threaded into the lower apertures 100 in cross-member 99. Drier 37 is thus held securely in position in relation to web 23 but may be readily and conveniently removed if desired. Drier 37 lying between printing cylinders 19 and 21 is retained in position by a bracket 108 similar to bracket 96, notched supporting bars 101 and 102 being provided to engage thumb screws 109.

It will be noted that brackets 108 are secured to main frame members 38 and 39 below the center of impression cylinder 13 so as to lie below swinging portion 111 of main frame members 38 and 39 described in detail in my copending application Serial No. 634,406. Brackets 112, secured to frame members 38 and 39, provide a suitable support for drier 37 located between printing cylinders 18 and 19. Brackets 112 include inwardly extending portions 113 provided with cross pieces 114 which are or may be integral with arms 113. Cross pieces 114 have threaded apertures 115 adapted to receive thumb screws 116 which engage notches or apertures in angle member 117 suitably secured to the ends of drier 37, as illustrated on Figure 1 of the drawing.

In operation, driers 37 are connected by conduits 86 and 89 to suitable sources of cold air and hot air, respectively. Chamber 44 is placed in communication with a suitable exhausting apparatus. The moist surface of the material

which is to be treated is spaced slightly from the driers 37 so that air blown upon it may act most effectively. As the material is advanced past the drier it first receives a blast of hot air tangentially directed from inclined slots 61 which dries the moist ink. Between each slot 61 and at each end of the row of slots 61, a suction nozzle 55, extending substantially the full width of the material being treated is preferably provided to withdraw the heated fluid. If desired, suction nozzles of suitable design may be provided at the ends only without departing from the spirit of the invention. It is obvious that in many specific applications of my novel drier it may be preferable to advance the drier over material under treatment which is held stationary. Slots 61 extend substantially across the full width of the surface to be treated which gives a uniform drying action without causing distortion which would otherwise result.

As the material advances past the zone of warm air issuing from chamber 46 through slots 61, it encounters tangentially directed blasts of cold air issuing from elongated inclined air slots 59. Suction nozzles 55, disposed between slots 59 and each end of the row of slots 59, withdraw the cool air blown upon the material. If desired, however, end nozzles alone may be provided as previously pointed out. Slots 59 preferably extend substantially the full width of the material being treated to insure equal cooling of the material being treated. Non-uniform shrinkage or expansion of the material under treatment is eliminated by the uniform distribution of the hot and cold blasts from my novel driving apparatus.

The surface being treated, after being dried by passage through the zone of heated air encounters the zone of cool air which cools the material under treatment, in this instance the inked surface of web 23, and crystallizes or dries the warm ink so that further printing may be done immediately upon the surface under treatment.

Heated and cooled air blown upon the material under treatment together with fumes which may arise in the case of a moist inked surface coated with volatile inks, are removed through nozzles 55, 65 and 69 which quickly remove the warm and cool air and the fumes overlying the surface permitting a successive and continuous application of fresh warm and cold air to quickly dry the ink.

Close and accurate register of succeeding printings is facilitated by my novel method and apparatus for drying the surface of material substantially without distortion and without non-uniform shrinkage or stretching of the material.

A further embodiment 48 of my novel drying apparatus is illustrated in Figures 1 and 6 of the drawings. This embodiment 48 of the drying apparatus is positioned on web roll stand 12 and receives web 23 as it leaves printing cylinder 21 of press 11.

It is to be understood that embodiment 48 of my drier may be used interchangeably with the embodiment 37 illustrated in Figures 1 to 4 of the drawings by altering the dimensions thereof and changing the manner of support.

With particular reference to Figures 1, 6 and 7, an outer casing member 131 comprising top wall 132, side walls 133 and end walls 134 encloses drier 48. Top wall 132 is provided with an opening 135. End walls or partitions 136 and 137 and partitions 138 and 139 define a recess or

chamber 141 in casing member 131 coextensive with aperture 135. A removable cover 142 closes chamber 141 at its top but permits ready access thereto when desired through aperture 135.

A plurality of nozzle members 143, spaced from each other to form ducts or channels 144 and preferably inclined as shown, are secured to longitudinally disposed metallic strips 145 for a purpose to be described. Wall 136 of chamber 141 is turned inwardly at 146 and has a downwardly extending portion 147. Elongated ducts or channels 148 similar to ducts 144 are provided by wall 149 of end nozzle member 143 and portion 147 of end wall 136. End wall 137 is turned inwardly at 151 and extends downwardly to provide a downwardly extending portion similar to portion 147 of wall 136. Elongated duct or channel 152, preferably inclined as shown, is provided between a wall of the other end nozzle member 143 and the downwardly extending portion of wall 131. Bars or strips of metallic material 154 rest on inturned portions 146 and 151 of the end walls 136 and 137 of chamber 141, and comprise supporting members for heating units 155 which may be readily removed from chamber 141 through aperture 135. Brackets 156, secured in any suitable manner to strips 154 at conveniently spaced intervals, support heating units 155 which are secured to said brackets by suitable means such as screws.

I have chosen to illustrate eleven such heating units, but it is to be understood that the number may vary in accordance with requirements dictated by specific conditions encountered in a particular application.

Heater units 155 may be of any well known type, but for purposes of illustration are of the type comprising an insulating strip 159 surrounded by the convolutions of coils of electric resistance wires or ribbons, the ends of which are connected to binding post 160 (Figure 7). Each binding post 160 comprises a threaded bolt 161 over which collar 162 is clamped by nut 163. The leads from the resistance coils are received between collar 162 and nut 163. Supply leads from a suitable source of electrical energy may be clamped between nuts 164 and 165.

Chamber 166, also within casing 131, is enclosed by end walls or partitions 167 and 168 and side walls 169 and 171. Nozzle members 143, spaced to form elongated ducts or channels 172, are secured to bars 145 for a purpose to be described hereinafter.

End wall 168 is turned inwardly at 173 and extends downwardly at 174. Elongated duct or channel 175 is provided by wall 176 of nozzle 143 and portion 174 of end wall 168.

Another duct or channel 175, preferably inclined as shown, is provided by wall 177 of nozzle 143 and portion 178 of wall 167.

Lateral passages 179 are in communication at their ends with spaces 181 which extend the length of casing 131 beside chambers 141 and 166. Walls 182 of passages 179 support a plate 183 provided with upturned lips 184. Lips 184 cooperate with lip 185 on partitions 167 and 136 to form ducts or nozzles 186, which communicate with spaces 181 through passages 179. Nozzle members 143 are provided with inturned lips 187 which define elongated nozzles or openings 188 extending substantially the full length of nozzle members 143 and which communicate with spaces 181 at the ends of nozzle members 143. End walls 134 of casing 131 are provided with upwardly turned lips 189 which cooperate 75

with lips 190 on walls 137 and 168 to form nozzles or passages 191 which communicate with spaces 181 near their ends and also through passages 192.

5 Partition 194, Figure 6, having a portion 195 in the plane of wall 133, divides conduit connection 196 into passages 197 and 198. Passage 197 communicates directly with chamber 141. Passage 198 is in communication with duct 199 between wall 133 and housing 201. Portion 195 of partition 194 forms the bottom of passage 198 and insures that a portion of the air directed into conduit connection 196 will enter duct 199. Conduit 203 provides communication between duct 199 and chamber 166. Air, or any desired cooling fluid, is supplied to conduit connection 196 by a suitable blower.

Conduit connection 204 is secured in wall 133 and opens directly into one of the spaces 181 which is in communication with passages 192, 179 and one end of nozzles 143 as described.

Conduit connection 204 is adapted for connection with a suction fan or other suitable exhausting apparatus by means of any convenient conduit (not shown).

Suitable flanges or supporting brackets 205 are provided on casing member 131 whereby it may be mounted on paper roll stand 12 to dry the ink on the surface of web 23 after passage through the last printing couple on press 11.

A separate heater 207 on paper roll stand 12 lies beneath drier 40. Heater 207 heats the material of web 23 by contact therewith and assists drier 40 in drying the ink on the surface and removing substantially all moisture from web 23 so that it may be rolled or otherwise conveniently disposed of for further handling as a finished printed article. Heater 207 serves also as a guiding surface to space web 23 slightly from drier 40.

Heater 207 comprises a frame 208 having an inwardly directed continuous flange 209. T-shaped stiffening braces 211 are suitably connected at each end to flange 209 in contact with the walls of frame 208.

A cover plate 212 overlies frame 208. Curved ends 213 of plate 212 provide smooth guiding surfaces to avoid tearing of web 23.

Electric heaters 214 which may, if desired, be of a type similar to the heaters described with reference to the chamber 141, are secured to flange 209 of the heater frame at spaced intervals beneath plate 212 so that the heat generated may be imparted to cover 212. I have chosen to illustrate seven such heaters, but it is to be understood that any suitable number may be employed depending upon the degree of heat to be applied and the kind and condition of the material undergoing treatment.

60 A cooling member 221 is located on paper roll stand 12 next to heater 207 and beneath chamber 166 of drier 39. Cooling member 221 is provided with passages 222 which, preferably, communicate at alternate ends to provide a continuous zig-zag passage extending from end to end of the cooling member. A threaded aperture 223 is provided in member 221 to which a pipe may be connected to conduct cold fluid through the zig-zag passage formed by passages 222. A second threaded aperture 224 provides means for connecting a pipe to drain the cooling fluid from the cooling member after it has served the purpose of cooling web 23 which passes over the cooling member. Cooling member 221 is mounted on paper roll stand 12 so that web 23 is spaced

slightly from duct 172 and nozzles 186, 188, and 191.

In operation embodiment 40 of my novel drier acts in a manner similar to that just described for drier 37. Air or other fluid is supplied under pressure through a suitable conduit (not shown) suitably connecting conduit connection 196 and a blower, for example blower 229, which may be conveniently mounted on paper roll stand 12.

Conduit connection 204 is connected with a 10 suction fan or other exhausting apparatus.

Web 23 passes under drier 40 and is spaced therefrom a suitable distance by lying over and in contact with heater cover 212 and cooling member 221. The heater and cooling member are provided to assure the thorough drying of 15 web 23 before it is finally coiled into a close compact roll or otherwise disposed of for convenient handling.

A portion of the air supplied to conduit connection 196 enters chamber 141 where it is heated by heaters in chamber 141 before it is blown through ducts 148 tangentially onto the moist surface of web 23. Thorough heating of the air and a hot blast on web 23 is assured by having 20 said heaters positioned as illustrated over ducts or channels 148. The heated current of air from ducts 148 is distributed uniformly throughout the width of web 23 and dries the moist surface thereof uniformly.

A portion of the air entering conduit 196 is directed into chamber 166 through duct 199, and is projected directly upon the surface of web 23 tangentially thereto through duct 172 uniformly from edge to edge of web 23. This air, since it is not acted upon by heaters, is comparatively cool and acts to crystallize the ink and cool web 23. It will be seen that web 23 progresses from a zone to which a blast of heated air is uniformly supplied to a zone to which a blast of cool air is uniformly supplied.

The heated and cooled air blown upon web 23 together with vapor and fumes from the ink being dried is continuously withdrawn through nozzles 143, 186, 188 and 191 so that the current of warmed and cooled air may act most effectively to dry and condition the surface under treatment.

In the illustrated embodiment plate 212 lies sufficiently high with respect to rollers 35 that web 23 is received at curved end 213 closely against plate 212 so that the suction created at nozzles 143, 186, 188 and 191 will not lift the material under treatment against the drier and so diminish the effectiveness of the current or blast of air from the drier. If desired, the force of the drying current from the drier may be regulated to repel the material under treatment from the face of the drier. The combined effect of the air and suction nozzles is preferably selected so that all of the air projected on the surface to be dried will be removed through the suction nozzles, thus securing a complete removal of the vapor and fumes overlying the surface. This result may be secured in the illustrated embodiment by the provision of a greater number of or larger exhaust nozzles with respect to the nozzles for furnishing the drying current.

The material of web 23 is threaded into press 11 after inserting it between guide rolls 27 and over guide roll 28 and over and under the various tensioning rolls as previously described, after which it is passed between each one of the printing cylinders and impression surface 14, by rotating the press slowly either by a main power drive or a hand wheel in the manner described in co-

5 pending application Serial No. 634,406. After the material has been passed through the impression surface 14 and final printing cylinder 21 it is passed over guide roller 35 and passed under drier 40 on web reel stand 12 as previously described.

It is preferable in event the press is to remain idle for a time that a "dummy" piece of material sufficiently long to extend from roller 27 through the press and under drier 39 be attached to the end of web 23 so that the dummy material may be carried through the guide roll and under the printing cylinders and through drier 39 after which it can be detached from the end of the material which has been passed through the press. Subsequent operation of the press with a fresh piece of paper or other material may be initiated by pasting or otherwise connecting its ends to the dummy strip, whereupon, when the machinery of the press is started, the dummy strip will draw the end of the new material through the guide rolls and the printing couple and under drier 40 and then may be detached from the initial end of the fresh stock and preserved for later use.

30 The invention may be embodied in other specific forms without departing from the spirit or essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

35 What is claimed and desired to be secured by United States Letters Patent is:

1. A drier comprising a casing formed as a 40 plurality of separate compartments severally connected to sources of heated fluid, a relatively cool fluid and vacuum, and a plurality of nozzles connected with said compartments, some of said nozzles being arranged to discharge heated fluid and immediately effect its removal by suction at one portion of said casing, and other nozzles being arranged to discharge cooled fluid and immediately effect its removal by suction at another portion of said casing.

2. A drier for drying and treating a web of 45 coated material comprising a series of nozzles arranged to discharge a heated fluid upon said web and a second series of nozzles arranged to discharge a cooling fluid upon said web immediately after said web has passed said first series of nozzles, and exhaust means positioned between the several nozzles for continuously and immediately removing said fluids and the gases arising from said web.

3. A drier designed to be positioned between successive coating means on a coating machine comprising an outer casing, a plurality of relatively closely spaced nozzles in one side of said casing connecting with the interior of said casing and discharging from said side, and partitions arranged to divide said casing into at least three chambers, each of said chambers having a plurality of said nozzles communicating therewith and said chambers constituting a heating fluid chamber, a cooling fluid chamber and an exhausting chamber respectively.

4. The combination defined in claim 3 wherein the nozzles are arranged at an angle to the 70 plane of said side and are designed to expel treat-

ing fluid in substantial tangential relation to said side.

5. A drier designed to be positioned between successive coating means on a coating machine comprising a casing having a plurality of independent chambers, a plurality of heating elements disposed in at least one of said chambers, means to conduct cooling fluid to at least one other of said chambers, and means to apply a vacuum to another of said chambers, and a plurality of series of nozzles communicating with said chambers, each series being arranged to communicate with only one of said chambers.

6. A nozzle construction for use in a drier having an exhaust chamber, a heating chamber and a cooling chamber, comprising a plurality of parallel tubes having substantially centrally disposed, longitudinally extending slits forming nozzles in the under sides thereof, connector members at opposite ends of said tubes adapted to support said tubes in spaced relation, said tubes forming longitudinally extending nozzles therebetween, end plates designed to close the ends of said tubes and said last mentioned nozzles, a partition engaging said end plates and extending over said tubes, said partition and said end plates forming a closed chamber communicating with said last mentioned nozzles, and a cover adapted to extend over said partitions and extend down to the under sides of said tubes, said cover being positioned in spaced relation to said partition and said end plates to form a chamber to communicate with said first mentioned nozzles.

7. In a printing press comprising an impression cylinder having a web to be printed wrapped in close contact about its peripheral surface, a plurality of spaced printing cylinders arranged about said impression cylinder and adapted to simultaneously contact said web and print successive registered printing impressions thereupon and treating means disposed about said impression cylinder between successive printing cylinders for treating each fresh wet printed impression before it advances to the next printing cylinder, each of said treating means comprising means for discharging warm fluid upon said fresh impression and means for discharging cool fluid upon said fresh impression in quick succession and means for withdrawing the vapors generated during said treating so that each printing impression on the web is thoroughly dried and hardened before the succeeding registered printing impression is made.

8. A drier for use in treating a coated surface comprising a casing having a plurality of spaced nozzle members arranged along one side thereof, said nozzle members being formed with openings leading externally of said casing and the spaces between said nozzle members providing passages leading externally of said casing adjacent said nozzle member openings, a chamber within said casing in fluid communication with said passages and a second chamber in said casing distinct from said first chamber in fluid communication with both ends of said nozzle members.

9. A drier of the type defined in claim 8, said first chamber being provided with a partition dividing it into separate chamber sections, each connected to a different group of said passages between the nozzle members.

10. In an intaglio web printing press of the type which comprises a large impression cylinder having a plurality of printing cylinders spaced therearound and a plurality of drying units po-

sitioned between successive printing cylinders for drying the fresh moist printed ink impression on the web after it has passed each printing cylinder, each of the drying units comprising means for directing heated dry air upon the fresh impression cylinder surface at a relatively high velocity, means for immediately and continuously exhausting said air as it rises from the drying web surface, means for thereafter directing cool air upon the partially dried impression substantially tangentially of the impression cylinder surface, and means for immediately exhausting said air as it rises from the web surface whereby said moist ink is quickly and thoroughly dried before it reaches the next printing cylinder.

11. A method of treating a freshly printed surface which comprises the steps of subjecting said surface continuously to the action of heated drying fluid under pressure while simultaneously and immediately withdrawing the fumes and vapors arising from the surface and immediately thereafter subjecting said surface continuously to the action of cooling drying fluid under pressure while simultaneously and immediately withdrawing fumes and vapors arising from said surface.

12. Apparatus for treating a freshly printed surface comprising means for subjecting said surface continuously to the action of heated drying fluid under pressure, simultaneously acting means for immediately withdrawing the fumes and vapors arising from said surface, means for immediately thereafter subjecting said surface continuously to the action of cooling drying fluid under pressure, and means acting simultaneously with said last named means for immediately withdrawing the fumes and vapors rising from said surface.

13. The method of drying a moving freshly printed sheet surface or the like which comprises passing the printed surface of the sheet in a convex path under tension, simultaneously directing a plurality of spaced blasts of drying fluid at an acute angle upon and confined along said printed surface generally against the direction of travel of the sheet, and immediately withdrawing the fumes and vapors arising from said surface.

14. Apparatus for drying a moving freshly printed sheet surface or the like which comprises a convex supporting means over which said sheet is tensed with its printed surface facing outwardly as it is being dried; concavely curved means closely adjacent said sheet for directing a blast of drying fluid upon said printed surface at an acute angle against the direction of travel of said sheet; means for confining said blast along said surface, against the direction of travel of said sheet, and means for immediately removing the fumes arising from said printed surface.

15. Apparatus for drying a moving freshly printed sheet surface or the like comprising convex supporting means over which said sheet is tightly drawn with its printed surface facing outwardly as it is being dried; a plurality of spaced, arcuately arranged nozzles disposed along the printed surface parallel to said convex supporting means for directing blasts of drying fluid upon said printed surface, said nozzles being positioned close to the printed surface and being adapted to direct said drying fluid at an acute angle to said printed surface and against the direction of travel of the sheet; means for confining said blasts along said surface against the direction of travel of said sheet; and means closely adjacent the print-

ed surface for removing the fumes and vapors arising from said surface.

16. Apparatus for drying a moving freshly printed sheet surface or the like comprising convex supporting means over which said sheet is drawn under tension with said printed surface facing outwardly while being dried; drying fluid supply nozzle means disposed closely adjacent said printed surface for directing drying fluid under pressure upon said printed surface at an acute angle against the direction of travel of said sheet; means for confining said fluid along said surface, against the direction of travel of said sheet, and suction nozzle means at opposite sides of said supply nozzle means.

17. Apparatus for drying a moving freshly printed sheet surface or the like comprising convex supporting means over which said sheet is tensed with its printed side facing outwardly while being dried; and a plurality of concavely arranged alternately disposed suction and drying fluid supply nozzles closely adjacent and substantially parallel to said printed surface, said supply nozzles directing successive blasts of drying fluid upon said printed surface at an acute angle against the direction of travel of said sheet; each of said supply nozzles being preceded by a suction nozzle toward which its discharged drying fluid passes after contacting the printed surface, and each of said suction nozzles following im- 30 mediately after a supply nozzle.

18. Apparatus for drying a moving freshly printed sheet or the like which comprises convex supporting means over which said sheet is drawn under tension with said printed surface facing outwardly as it is being dried; a supply nozzle disposed close to said surface for directing drying fluid upon said surface at an acute angle against the direction of travel of the web; an exhaust nozzle disposed close to said surface and positioned to be traversed by said surface prior to the supply nozzle; and means for directing and confining the flow of fluid discharged by said supply nozzle closely along said surface until it reaches said exhaust nozzle.

19. Mechanism for drying a freshly printed paper web, comprising pressure means for creating a current of air and for directing said air current along the freshly printed surface of the web, and exhaust means separate from said pressure means for exhausting the air current after it has contacted with said surface, said exhaust means having greater capacity than said pressure means.

20. A method of drying a freshly printed paper web which consists in forcing a current of air along the freshly printed side of the web while substantially confining said air current to said printed side, and then exhausting the air current away from said web, the rate of exhaust exceeding 25 the rate of supply of air by said current.

EMIL ERICKSSON.
